MOBILE STAND FOR A FAN

Carl Krauss, Chicago, Ill.

Application July 9, 1957, Serial No. 46,872

Term of patent 14 years

(Cl. D26—7)

FIG.1.

FIG.2.

FIG. 3.

FIG. 4.

Fig. 1 is a perspective view of a mobile stand for a fan showing the front of my new design;

Fig. 2 is an end elevational view;

Fig. 3 is a rear elevational view; and

Fig. 4 is a top plan view thereof.

The broken line showing of a representative fan is for illustrative purposes only.

I claim:

The ornamental design for a mobile stand for a fan, substantially as shown and described.
